UNITED STATES PATENT OFFICE.

HERBERT B. NICHOLS, OF METHUEN, MASSACHUSETTS, ASSIGNOR OF ONE-HALF TO
HENRY C. DOUGHTY, OF METHUEN, MASSACHUSETTS.

LIQUID-SOAP-DISPENSING DEVICE.

1,165,279.

Specification of Letters Patent. Patented Dec. 21, 1915.

Application filed May 29, 1914. Serial No. 841,890.

To all whom it may concern:

Be it known that I, HERBERT B. NICHOLS, a citizen of the United States, residing at Methuen, in the county of Essex and State 5 of Massachusetts, have invented new and useful Improvements in Liquid-Soap-Dispensing Devices, of which the following is a specification.

An object of the invention is to provide 10 a simple device for use in dispensing liquid soap and the like and which is particularly adaptable for use in wash rooms, thus obviating the necessity of providing the usual cakes of soap and which are oftentimes un- 15 sanitary for the reason that they are used to wash the hands and faces of different people.

The invention contemplates, among other 20 features, the provision of a receptacle or container which can be arranged on a suitable bracket and which contains the liquid soap, with means on the receptacle and supported thereon whereby quantities of the liquid soap can be readily removed from 25 the container or receptacle by a slight movement of a plunger or member which determines to a certain extent the amount of liquid soap to be used in the operation of washing the hands or face.

30 In the further disclosure of the invention reference is to be had to the accompanying drawings, constituting a part of this specification; in which similar characters of reference denotes corresponding parts in all 35 the views, and in which:

Figure 1 is a vertical sectional view taken through the device; Fig. 2 is a horizontal sectional view taken on the line 2—2 in Fig. 1; and Fig. 3 is a plan view.

40 Referring more particularly to the views, I provide a receptacle 10 which is preferably made of glass and encircled by a band 11 constituting a part of a suitable bracket 12 whereby the receptacle can be supported 45 over a basin or wash stand, the band 11 being preferably countersunk in an annular recess 13 in the receptacle so that the face of the band will lie flush with the periphery of the receptacle, thus presenting a neat and 50 effective appearance and causing the band to support the receptacle in vertical position. A tubular member 14 provided with a plurality of opposed openings 15 in its lower end is arranged within the receptacle, 55 with its lower end abutting against the bot-

tom 16 of the receptacle and its upper end lying adjacent to the top 17 of the receptacle. The bottom 16 is provided with an opening 18 through which passes a nozzle member 19 of a tubular nature, said nozzle member including an integral threaded shank 20 extending in the lower end of the tubular member 14 and adapted for threaded engagement therewith, thus holding the nozzle member in position with respect to 60 the receptacle and whereby communication between the tubular member and the nozzle member is established. The inner end of the shank terminates in a seat 21 preferably beveled and upon which normally reposes 65 the body 22 of a valve or plunger 23 which, when in normal position, will close the openings 15, said valve or plunger having a reduced stem 24 projecting through the tubular portion of the nozzle member and depending exteriorly thereof.

A closure 25 is provided for closing the inlet opening 26 formed in the top 17 of the receptacle and the said closure includes an integral threaded shank 27 which is adapted 80 for interior threaded connection with the upper end of the tubular member 14 so that the nozzle member 19 and closure 25 constitute the means for supporting the tubular member within the receptacle while the closure 85 also closes the inlet opening 26 in the top of the receptacle. The closure 25 is preferably provided with a plurality of apertures 28 to permit of the insertion of a wrench or the like therein whereby to remove the closure for the purpose of filling the receptacle, said apertures being also provided to permit air to enter the receptacle and thus result in a clear flow of the fluid 90 through the nozzle when the plunger or 95 valve is actuated.

When the plunger or valve is in its normal position it will be seen that there is a space between the upper end of the plunger and the shank 27 of the closure and that the plunger normally closes the openings 15 in the tubular member. Now when it is desired to obtain a quantity of the soap the hand is placed beneath the receptacle and an upward push imparted to the stem of the plunger 23, thus unseating the same and uncovering the openings 15 so that the liquid soap can flow outwardly through the nozzle into the palm of the hand of the operator. The upward movement of the plun- 105 110

ger is limited by the engagement of the upper end of the body 22 of the plunger with the closure 25 and when the upward pressure on the stem of the plunger is released the weight of the plunger will cause the same to gravitate into normal position and again repose upon the seat 21 to close the openings 15.

From the foregoing description it will be seen that the device described is of a simple construction, consists of few parts and can be readily operated, while at the same time it will be clean and sanitary and obviate the necessity of using the usual cake of soap and which is considered unsanitary for the reason that it oftentimes is used by different persons after being previously soiled.

Having thus described my invention, I claim:

In a liquid soap dispensing device comprising a receptacle including a top and bottom, each provided with an opening, an annular flange formed on the wall of one of

said openings, a closure having an annular rib formed thereon, said closure disposed within the flanged opening and extending into the receptacle, a nozzle member disposed in the opening in the bottom of the receptacle and extending therethrough, a valve seat formed on the upper end of said nozzle member, a tubular member arranged in the receptacle and having the ends thereof threadedly engaging the shanks of the nozzle and closure, said tubular member having a plurality of openings adjacent the lower end thereof, a plunger valve arranged to slide within the tubular member and normally closing the openings, and a stem depending from the plunger valve and passing through the nozzle member and projecting exteriorly therethrough.

In testimony whereof I affix my signature in presence of two witnesses.

HERBERT B. NICHOLS.
